(57) CLAIM

The ornamental design for a bingo ink marker bottle, as shown and described.

DESCRIPTION

FIG. 1 is an exploded perspective view of a bingo ink marker bottle showing our new design with a cap thereof;

FIG. 2 is a top plan view thereof;

FIG. 3 is a bottom plan view thereof; and,

FIG. 4 is a right side elevational view thereof, the left side, front and rear elevational views being mirror images thereof.
